UNITED STATES PATENT OFFICE.

EARLE J. WENTZ, OF GAFFNEY, SOUTH CAROLINA, ASSIGNOR TO HOPEDALE MANUFACTURING COMPANY, OF MILFORD, MASSACHUSETTS, A CORPORATION OF MASSACHUSETTS.

FEELER-LOOM.

1,347,726.

Specification of Letters Patent. Patented July 27, 1920.

Application filed August 14, 1917. Serial No. 186,208.

To all whom it may concern:

Be it known that I, EARLE J. WENTZ, a citizen of the United States, residing at Gaffney, in the county of Cherokee and 5 State of South Carolina, have invented certain new and useful Improvements in Feeler-Looms; and I do hereby declare the following to be a full, clear, and exact description of the invention, such as will enable others skilled in the art to which it 10 appertains to make and use the same.

The present invention relates to an improvement in feeler looms and more particularly the invention relates to a device 15 for such looms whereby the filling detector mechanism may be rendered inoperative or functionless at predetermined times.

Feeler looms are a type of weft replenishing loom wherein a filling feeler mechanism determines the state of exhaustion of the filling in the active shuttle, and when the filling has been exhausted to a critical or predetermined extent initiates the weft replenishing operation. These looms are 20 most commonly employed in the production of the higher grades of fabrics in which the presence of a mispick, that is to say, a short weft, is a detrimental blemish. The filling feeler mechanism is employed to initiate 25 the weft replenishing operation for the purpose of obviating these mispicks. Feeler looms are also provided with one or more filling detector mechanisms, which usually 30 perform the function of causing loom stoppage on the detection of filling absence. The filling feeler mechanism of feeler looms is usually adjusted so that the weft replenishing operation is initiated when there is 35 sufficient filling in the shuttle for the laying of two or three complete wefts in the shed. It has sometimes been found necessary or 40 desirable, however, to adjust the filling feeler mechanism so that the filling may completely exhaust before the weft replenishing operation is initiated. This is the 45 case where feeler looms are employed for the production of the poorer grades of fabrics, in which the presence of a mispick is not a detrimental blemish. Where the filling 50 feeler mechanism of a feeler loom is so adjusted that it permits the filling to completely exhaust before the weft replenishing operation is initiated, it is obvious that

some provision must be made for preventing the filling detector mechanism from detecting the filling absence caused by the complete exhaustion of the filling and thereby setting the loom stopping devices in operation to stop the loom. Accordingly, it is the object of the present invention to produce a feeler loom having a device which will operate to render the filling detector mechanism inoperative or functionless when the weft replenishing operation is initiated on an indication of complete or substantial 55 exhaustion of the filling. To the accomplishment of this object, the invention consists in the feeler loom hereinafter described and particularly pointed out in the appended claims.

The preferred form in which it is contemplated embodying the present invention is illustrated in the accompanying drawings, in which Figure 1 is a plan of a portion of the weft replenishing end of a feeler 65 loom; and Fig. 2 is a side elevation, partly in section, of some of the parts shown in Fig. 1.

The device of the present invention for rendering the filling detector mechanism of feeler looms inoperative or functionless at predetermined times may be applied to any usual or preferred type of feeler loom. The loom illustrated in the drawings is of that type in which the filling feeler mechanism is located at one side of the loom and the weft replenishing mechanism is located at the other side of the loom. So far as the present invention is concerned, however, both these mechanisms may be located on 70 the same side of the loom. The usual filling detector mechanism for causing loom stoppage on the detection of filling absence is shown in the present instance as located adjacent the weft replenishing mechanism, 75 although the device of the present invention would be just as applicable in its control of the filling detector mechanism if the latter were located adjacent the filling feeler mechanism.

The feeler loom illustrated in the drawings comprises a lay 5 mounted for swinging movements toward and from the breast beam 6. The weft replenishing mechanism, of which the hopper is shown at 7, is connected by means of a hollow rock or change 105

shaft 8 with the filling feeler mechanism (not shown) located at the opposite side of the loom. When the filling feeler mechanism indicates critical or predetermined exhaustion of the filling in the active shuttle, the change shaft 8 is oscillated, and thereupon the hopper arm 9 fixed on the change shaft swings to the right, viewing Fig. 2, and the weft replenishing operation is thereby initiated. The filling feeler mechanism, the change shaft 8 and the hopper arm 9 constitute what is known in feeler looms as the loom controlling devices. The filling detector mechanism, indicated generally at 10, comprises a filling fork 11 which is pivoted at 12 on the rear end of a detector slide 13 mounted for sliding movements toward and from the lay in a bracket 14 secured to the breast beam 6. The tail 15 of the filling fork 11 is adapted for co-operation with the weft hammer hook 16 on the forward movement of the weft hammer 17, with which the hook 16 is connected, whenever there is filling absence on the corresponding beat-up of the lay. This beat-up of the lay, which occurs when the shuttle is boxed at the side of the loom on which the filling detector mechanism is located, is known as the filling detecting beat. When filling is present on this beat, the fork is tilted and the weft hammer hook 16 moves forward without co-operating with the fork tail 15; but when filling is absent on this beat, the fork remains quiescent, and consequently the weft hammer hook on its corresponding forward movement co-operates with the fork tail 15 to move the slide 13 forward. The forward movement of the slide 13 oscillates a stop arm 18 which is secured to a stop shaft 19 journaled within the hollow change shaft 8. The oscillation of the stop arm 18 and stop shaft 19 causes an actuation of the loom stopping devices and a consequent stoppage of the loom. The above-described parts and their mode of operation are well known to those skilled in the art.

As was stated in the introduction to the descriptive portion of this specification, the operation of the weft replenishing mechanism of a feeler loom is usually initiated on the indication of critical or predetermined exhaustion of filling in the active shuttle by the filling feeler mechanism. Usually this critical or predetermined exhaustion of the filling is indicated at a point sufficient to permit the shuttle to accomplish several picks before complete exhaustion of the filling, so as to obviate the possibility of a miss pick. In such cases the filling detector mechanism is brought into operation to effect loom stoppage only in the event of complete exhaustion of the filling, or in the event of breakage of the filling. But, in those cases where the filling feeler mechanism is

so adjusted that the filling in the active shuttle may completely exhaust before the weft replenishing operation is initiated, it will be obvious that when the shuttle arrives at the weft replenishing side of the loom, 70 the filling may be absent and, consequently, if the filling detector mechanism is located on this side of the loom, it may cause loom stoppage at the same time the weft replenishing operation takes place, unless provision is made for rendering the detector mechanism functionless at this time. The device of the present invention for rendering the filling detector mechanism inoperative or functionless on the detecting beat 80 following the indication of predetermined exhaustion of filling in the active shuttle (where the feeler mechanism is so adjusted that this predetermined exhaustion may be complete exhaustion), comprises a fork actuating member or cam 20 which is provided with an upwardly projecting finger 21. The finger 21 is adapted, when the weft replenishing operation is initiated, to lift the fork tail 15 above the path of motion of the weft hammer hook 16, and for this purpose the finger 21 is positioned under the side 22 of the fork tail 15, and the cam member 20 is connected with the hopper arm 9 so as to be actuated thereby when the latter is oscillated 90 on an indication of predetermined exhaustion of the filling by the filling feeler mechanism. The connections between the cam member 20 and the hopper arm 9 consist of a link 23 which is loosely connected at 100 its rear end with an arm 24 extending downwardly from the cam member 20 and which is loosely connected at its forward end with an arm 25 extending downwardly and laterally from the hopper arm 9. The construction and arrangement of the connection between the fork actuating cam member 20 and the hopper arm 9 are such that during the regular weaving operation of the loom the finger 21 is normally held in the position 110 shown in Fig. 2 with its upper end lightly engaging the under surface of the side 22 of the fork tail 15. The cam member 20, therefore, does not during the regular weaving operation of the loom interfere with 115 the proper functioning of the filling fork. The operation of the feeler loom illustrated in the drawings embodying the device of the present invention is described as follows: The filling feeler mechanism indicates predetermined exhaustion of the filling in the active shuttle, and thereupon the hopper arm 9 oscillates or swings to the right, viewing Fig. 2, to initiate the weft replenishing operation. The oscillation of the hopper arm 9 pulls the link 23 forward and thereby oscillates the cam member 20 to raise the finger 21 and lift the fork tail 15 above the path of movement of the weft hammer hook 16. These movements all 120

take place on the same beat-up of the lay on which the filling feeler mechanism indicates the predetermined exhaustion of filling; consequently, on the succeeding beat-up of 5 the lay, which is the filling detecting beat-up, and also the weft replenishing beat-up, the weft hammer hook on its corresponding forward movement will not coöperate with the fork tail 15 and the detector slide 13 10 will remain quiescent, and therefore the loom will not be stopped although the filling may be absent. On the completion of the weft replenishing operation, the lay beats backwardly, and coincident therewith 15 the hopper arm 9 returns to its normal position, thereby returning the cam member 20 and the finger 21 to their normal position to permit the filling fork to resume its normal function of detecting the absence or 20 presence of filling, and controlling the loom stopping devices accordingly.

The applicability of the device of the present invention to various types of feeler looms having been indicated and its mode 25 of operation with respect to a particular type of feeler loom having been described, it will be understood that the invention is not limited to the precise arrangement shown in the drawings and described above 30 but may be employed in other forms within the scope of the following claims.

What I claim as new is:—

1. A loom having, in combination, a filling detector mechanism including a filling 35 fork for causing loom stoppage on the detection of filling absence, a weft replenishing mechanism, means for initiating the weft replenishing operation, and means for tilting the filling fork to render inoperative

the filling detector mechanism on the initiation of the weft replenishing operation. 40

2. A loom having, in combination, loom controlling devices including a hopper arm, a stop shaft, a filling detector mechanism connected with the stop shaft adapted to 45 actuate the latter on detection of filling absence, and connections between the hopper arm and the fork tail of the filling detector mechanism constructed and arranged to lift the fork tail on an actuation of the loom 50 controlling devices.

3. A loom having, in combination, loom controlling devices including a hopper arm, a filling detector mechanism connected with the stop shaft and adapted to actuate the 55 latter on filling absence, and connections between the hopper arm and the fork tail of the filling detector mechanism whereby the latter is rendered inoperative on an actuation of the former. 60

4. A loom having, in combination, a weft replenishing mechanism, a lay, a filling detector mechanism including a filling fork for causing loom stoppage on the detection of filling absence, and means for tilting the filling fork to render the filling detector mechanism inoperative on the beat-up of 65 the lay on which the weft replenishing operation occurs.

5. A loom having, in combination, a filling detector mechanism including a filling fork for causing loom stoppage on the detection of filling absence, and means for tilting the filling fork to render the filling detector mechanism inoperative to perform 70 its loom stopping function at predetermined times. 75
